COMBINATION GARMENT AND BRASSIERE

Hyman Robins, Brooklyn, N. Y.

Application November 24, 1950, Serial No. 197,431

3 Claims. (Cl. 2-42)

1

The present invention relates to improvements in combination garment and brassiere and has for an object to provide a built-in concealed brassiere for such garments as bathing suits, sun-dresses, playwear and other ready-to-wear items wherever applicable.

Another object of the invention is to provide, in a combination garment, a novel form of brassiere which, in structure and function, is designed to perfect the figure and to give the wearer comfort, support and proper uplift.

A further object of the invention is to provide an improved combination garment in which bones or other stays are incorporated in the brassiere section to retain the cup shape for contour and at the same time to produce a garment which at the brassiere section is not bulky and is practical for all sizes.

A still further object of the invention is to provide an improved combination garment and brassiere in which such garment is perfected for strapless wear in that the stay construction under the tension produced by application of the garment to the bust will prevent sagging of the upper portion of the garment.

With the foregoing and other objects in view, the invention will be more fully described hereinafter, and will be more particularly pointed out in the claims appended hereto.

In the drawings, wherein the symbols refer to like or corresponding parts throughout the several views,

Figure 1 is a perspective view of the improved combination garment and brassiere in the position of use.

Figure 2 is a similar view, on a larger scale, with upper portions of the outer garment removed and showing the lining arranged to constitute the brassiere shown as actually applied in use.

Figure 3 is a rear elevational view showing the combination garment opened down the back and showing in interior elevation the midriff section and the brassiere sections of the lining with the end and side portions of the elastic tape free of the sides of the garments and emerging from the side seams.

Figure 4 is an enlarged fragmentary interior elevational view of the combination garment and brassiere showing a bone section partly broken away with the gathering of the lining exaggerated along the lower edge of the brassiere incident to the contraction of the elastic tape.

Figure 5 is a fragmentary enlarged section of the lining of the garment arranged to form the brassiere and with parts of the garment shown

and with the elastic tape in the contracted position.

Figure 6 is a similar comparative view showing the tape and lower portion of one of the cups expanded about the bust.

Figure 7 is a horizontal sectional view taken on a smaller scale on the line 7-7 in Figure 5 and showing the contracted condition of the elastic tape with one of the cups shown in an initial position of application to the bust.

Figure 8 is a similar comparative view showing the application of the brassiere and outer garment material stretched over the bust when the elastic tape is drawn taut and fixed at the back of the body, this Figure 8 being taken on the line 8-8 in Figure 6.

Figure 9 is a vertical sectional view with portions of the garment and lining broken away and showing the application of the brassiere and garment to the bust in the stretched condition of the elastic tape, and

Figure 10 illustrates an internal elevational view with parts broken away and parts shown in section of the improved garment lining arranged as a brassiere with side panels of the garment in dotted lines and with the ends of the elastic tape detached and with the tape in the contracted position.

Referring more particularly to the drawings which illustrate only a single embodiment of which the invention is susceptible, such invention is illustrated in connection with a bathing suit of which 15 designates generally the lower section which may be a panty or skirt section and may be formed of inner and outer parts. The garment also comprises a midriff section 16 and an upper or bust section 17. The side and back sections are indicated generally at 18 and 19, such sections meeting in the back and having a zipper or other suitable fastenings 20, as shown in Figure 3, to secure the garment about the person of the wearer.

The garment as to its various sections will be made with outer garment or dress material and with an inner lining.

By reference to Figures 7, 8 and 9 the outer garment material is designated at 21 and the inner lining material at 22. Throughout the garment with the exception of the bust section the lining may be of usual lighter lining material which may have stretch in one or both directions if desired but in the brassiere section of the garment the lining 22 is preferably of the same material as the outer wall of dress material 21 and preferably, although not necessarily, the bras-

sière lining 22 is non-stretchable in either direction.

Moreover the outer wall 21 of dress material is preferably unconnected to the lining throughout the entire area of the various sections of the garment except that outer dress wall 21 and lining 22 are connected along the upper edge of the garment including the brassière section 17 and the side panels 18, 19 and such outer dress wall 21 and lining 22 are also connected together along the open back of the garment as at the zipper opening 20. In other words the lining 22 throughout at least the midriff and brassière sections 16 and 17 of the combination garment is entirely free from the outer wall of dress material 21 except at the edge portions thereof. Consequently the brassière section of the garment including both outer wall 21 and inner wall 22 may accommodate itself to the bust in an action in which the two walls 21 and 22 adjust themselves freely of one another to the contour lines of the bust which makes for smoothness in conformation and avoids bulkiness. The method of securing the walls 21 and 22 together at the edges is preferably by stitching as indicated in the drawings.

The sides of the garment may be provided with stays or bones 23. The lining or internal wall 22 of the brassière section is formed with cups 24 and 25 in the cups are produced vertical and horizontal darts 26 and 27.

The brassière as such is constituted of the lining portion 22 only and the outer dress wall 21 is merely made in this section of sufficient fullness or looseness so as to shape itself snugly over the cups of the internal brassière section 22 as the garment is applied to the figure of the wearer.

At the opposite side portions of each cup are provided bones or stays 28 and 29 erected substantially vertically, such bones or stays being contained in casings 30, as clearly appears in Figure 10. These stays are of bone, steel or other material possessing inherent elasticity, the same being wider than they are thick so as to be bendable flatwise within their elastic limits but being strongly resistant to bending edgewise and having a substantial edgewise rigidity. These stays 28 and 29 have their upper ends extending substantially all the way to the upper edge of the garment which is the upper edge of the brassière section and continuing all the way down substantially vertically to a point just short of the midriff section 16. An elastic tape 31 is sewed or otherwise affixed only to the inner lining wall 22 at the lower portion of the brassière section and between the brassière section and the midriff section 16. This tape being entirely free of the outer garment wall 21 as appears to best advantage in Figure 9. Preferably the lower ends of the stays 28 and 29 terminate at or just above the upper edge of this elastic tape 31 which extends in a substantially horizontal line beneath the brassière section so as to fit snugly beneath the bust in the act of applying the garment to the figure of the wearer. The stays 28 and 29 are set in the cups with their edgewise dimensions substantially parallel with the walls 21 and 22 so that they may be received flatwise against the sides of the breasts. These stays 28 and 29 are slightly longer in vertical height than the vertical distance between the top edge of the brassière section and the tape line 31 which arrangement imparts to the stays 28 and 29 an initial slight bend which has a tendency to preform the brassière section into natural cups of a very shallow depth as in-

dicated in Figure 7 but adaptable as a matter of origin for application to the bust giving to the garment a bend or bias which preliminarily predisposes such garment to most readily fit the figure in the act of tightening and drawing the brassière over the bust.

It will also be noted, particularly from Figures 5 and 10, that the lower ends of the stays 28 and 29 are set closer together than the upper ends of such stays and that the tape 31 is sewed to the lower edge of the brassière section 22 while stretched and expanded so that when released the elastic band or tape 31 will contract thus drawing the lower ends of the stays closer together and incidentally forming the gathers indicated at 32 particularly in Figure 5. Thus the elastic tape 31 in the contracted position will draw the lower ends of the stays together and gather part 22 along its lower edge.

In Figure 3 the side seams are indicated at 33 and 34 and such side seams are formed by sewing the inner brassière wall 22 and the midriff lining walls 16^a to the lining walls 18^a and 19^a of the side sections. The intermediate portion only of the tape is sewn or otherwise affixed to the lower edge of the brassière section 22 and this intermediate portion of the elastic tape 31 extends from side seam 33 to side seam 34. At the side seams 33, 34 the ends 31^a and 31^b of the elastic tape emerge inwardly of the side linings 18^a and 19^a and these tape ends 31^a and 31^b are not attached to any part of the garment but are entirely free to be passed around to the back of the wearer. The tape ends may be tied at the back but preferably they will have some form of complementary fastening. A preferred form of fastening is an adjustable one. For example a hook 35 on one tape end may cooperate with a series of openings or eyelets 36 on the companion tape end so that the hook 35 may be selectively engaged with any particular eyelet in accordance with the girth dimensions of the wearer.

As shown in Figure 9 the elastic tape 31 may be stitched by the same rows of stitching that are employed to attach the brassière inner wall 22 to the midriff lining section or panel 16^a. As shown in Figure 9 also the elastic tape 31 is preferably outward of the overlapping sections of the walls 22 and 16^a to avoid pulling the stitches and to draw both walls about the torso and to avoid bulkiness.

The material 22 of the brassière inner section, which as stated before is preferably of a heavier than ordinary lining material, is preferably brought down from the brassière section in a central strip 37 of inextensible material which is sewed or otherwise affixed to the midriff lining panels 16^a.

In the use of the garment, such garment is stepped into and pulled upwardly over the body with the back section open as indicated in Figure 3; or in the case of a skirt the garment may be stepped into or pulled over the head. The brassière section will be originally in the contracted condition shown more particularly in Figures 5 and 7 and as thus contracted it is applied against the bust. With the back of the garment still open as shown in Figure 3 the two tape ends 31^a and 31^b are then passed around to the back of the body while at the same time stretching such tape. This stretching pressure will take effect from the side seam lines 33 and 34 and will not affect the side panels 19^a and 18^a. By this action the front brassière section 21, 22 alone will be stretched laterally in a horizontal direction. This action

will also cause the intermediate portion of the tape 31 at the front of the garment to be drawn tight along a line just beneath the bust. The tape is then secured at the back as by engaging the hook 35 with a selected eyelet 36 in such wise 5 that the brassière section and the tape 31 will remain in an extended taut condition.

As soon as the pressure of the expanding tape is communicated to the inner brassière section 22, it will draw this section toward the body causing 10 the stays 28 and 29 to ride over the curved side walls of the breasts and thus to turn gradually from position of Figure 7 to that shown in Figure 8 in which from a flatwise standpoint the stays 28 and 29 are turned angularly through quite a wide 15 angle short of a right angle. Also these stays 28 and 29 are caused to assume the curvature of the bust in a longitudinal or vertical direction. The greater this curvature the closer the bent stays approach the elastic limit and consequently they 20 become more rigid in a vertical upstanding sense and impart greater uplift and also sustain the upper line of the garment against sagging and at a more permanent line so that the use of shoulder straps may be entirely dispensed with, a feature which recommends the construction for incorporation in formal wear.

Incident to the expansion of the tape 31 in the act of applying the garment to the bust, the lower 30 ends of the stays 28 and 29 will be separated and the gathers 32 will be stretched out into a taut condition.

Figure 5 shows the contracted position of the garment before it is applied and Figure 6 shows the applied position of the garment in elevation in which the tape is shown as stretched, all the 35 gathers removed and the stays 28 and 29 have been turned so that they are viewed partially edge-wise and are given a more pronounced bowed appearance.

The upper edge of the garment is also preferably reinforced by a taping 38 to prevent the fabric from stretching and for holding the garment snugly to the body. Due to the fact that the lower 45 ends of the stays 28 and 29 are adjacent or connected to the upper end of the elastic tape 31, the stretching of the tape not only stretches the gathers 32 at the lower portion of the brassière but this stretching action is communicated through the stays to all parts of the cups between the 50 stays and tends to stretch out any looseness or gathers that may occur due to the relaxed position of the garment for which compare Figures 5 and 6.

Referring more particularly to Figures 7 and 8, by comparative views the action of pulling and stretching the tape 31 is illustrated in which the cups are stretched tight across the breasts with the bones or stays turning gradually as they slide inwardly along the curved surfaces of the breasts and assume the shape and conformation of the breasts which puts the same under elastic tension and imparts greater upstanding rigidity to such stays.

Due to the fact that the walls 21 and 22 are completely unconnected across the area of the brassière section, the inner wall 22 which is the only wall directly connected to the elastic tape 31 is pulled inwardly and stretched over the bust so as to secure accurate conformation, while the 70 outer loose wall 21 follows and adjusts itself in a natural manner to the same contour without creating any bulkiness or lumps and imparts to the garment a smooth and wrinkle-free appearance. At the same time the stays being under tension 75

form rigid upstanding supports of greater dependability which will prevent the garment from sagging and producing unsightly gaps along the upper edge of the garment. Such upper edge will be retained at a uniform and preselected level so that throughout the entire time that the garment is worn it will preserve the initial attractive appearance to which it has been initially adjusted.

Figure 9 also shows how the complete detachment between the walls 21 and 22 permits the outer wall 21 to be free of the elastic tape 31 but to be permitted to follow naturally the contour of the bust in the fitting action of the garment to the body of the wearer.

After the free ends 31^a and 31^b of the tapes have been adjusted and secured in the back of the wearer, the back of the garment may be zipped into a closed position over these tapes, it being comparatively easy to perform this fastening operation due to the fact that the side seams 33 and 34 and the entire front panel of the garment including brassière and midriff sections have been drawn tightly by the elastic tape around to positions at the side of the body so that the side and rear panels 18^a and 19^a offer no resistance to the zipping or closing of the garment at the back portion 20.

The vertical darts under the bust and also the side bust darts provide the necessary shape. The curving of the bones on the sides of bust are for perfection of cupping and to secure a firmer uplift. The elastic band which is sewn to the inner wall 22 all the way across the front of the garment and to the side seams 33, 34 supports bust firmly to body for a perfect uplift. The elastic band 31 emerges from the side seams with its ends hanging loose for adjustability and security, the ends being closed preferably with the hook and eye. At 39 and 40 are shown the seams which 40 connect the top brassière part to the midriff lining 16^a of the garment.

The invention provides a completely built-in concealed brassière for garments dispensing with the use of shoulder straps in all sizes and having the effect to give the wearer comfort, support and proper uplift, at the same time perfecting the figure and avoiding sagging or displacement of the garment particularly at the upper portion thereof.

The combination garment according to the present invention can be worn without any other undergarment beneath it.

The invention finds great utility in accommodating the brassière to busts of various sizes in that the arrangement of parts enables the cups to be altered in size to correspond to varying bust sizes. The garment forms cup sizes, small, medium and large, depending on the bust size of the wearer. The various cup sizes are brought about by the amount of stretch given the elastic tape. When the tape is stretched to its maximum length the cup size is smallest and when the elastic tape is stretched to a minimum the largest cup size is formed.

By regulating the amount of stretch of the elastic tape any intermediate cup size can be formed.

The amount of curvature of the stays forms the various cup sizes and is accomplished by the action of the stretch on the lower ends of the stays and this is achieved by the elastic tape as it is connected to the lower ends of such stays. In the act of imparting stretch to the elastic tape, the ends of such tape are carried to the back of the wearer and in so doing the cups are applied to the bust. This application of the cups to the bust is brought about by the fact that the tape is con-

nected to the lower ends of the stays. As the cups are forced over the breasts the stays are required to assume the curvature of the breasts which causes the stays to become bowed to greater or lesser extent according to the bust size. Therefore, the degree of this bowed condition of the resilient stays is automatically controlled by the amount of stretch of the elastic tape. The result, therefore, is to create the bowing to conform to the wearer's bust size.

While it has been heretofore stated that the elastic tape is connected to the stays it will be understood that this connection may be either direct or indirect. In the drawings, showing only one embodiment of this invention, the connection is made by stitching the elastic tape to the casings in which the stays are housed. This causes the stays to move in accompaniment to the stretched conditions in the elastic tape.

It will be understood that the improved brassière may be used in combination with the garment or separately as desired.

Although I have disclosed herein the best form of the invention known to me at this time, I reserve the right to all such modifications and changes as may come within the scope of the following claims.

What I claim is:

1. A brassière comprising a flexible fabric wall having a lower edge and said wall having cups formed therein, flat elastic stays secured to side portions of said cups and biased to a slight outwardly bowed condition to preform the brassière into natural cups of shallow depth, and an elastic tape secured to the entire lower edge of the fabric wall in stretched condition so as to be disposed beneath said cups and connected to the lower end portions of said stays to move such lower portions of the stays apart distances proportional to the amount of stretch given the tape, said tape also adapted to draw the brassière including the cups and stays against the breasts with the cups expanding to receive the breasts of the wearer and the stays moving over the sides of the breasts to further bow the same to thus alter the sizes of the cups in conformity with the size of the bust.

2. A combination garment including a brassière comprising a flexible fabric wall having a lower edge and said wall having cups therein, resilient stays secured to side portions of said cups, and a resilient tape secured in stretched condition to the entire lower edge of said fabric wall so as to be disposed below said cups and connected to the lower end portions of said stays whereby when stretched the tape will spread the lower portions of the stays in proportion to the degree of stretching and when the tape is passed about the body of the wearer will force the cups including the stays over the bust to proportionately bow the

5
10

8
stays and accordingly alter the size of the cups to accommodate varying sizes of breasts, an outer garment secured at its upper edge only to the upper portion of said brassière fabric wall whereby to freely and naturally accommodate itself to the conformation of the cups of the brassière, side and rear portions for said outer garment, and fastening means for the rear portions of said outer garment adapted to be fastened independently of and subsequent to the tape.

3. A combination garment including a brassière comprising a flexible fabric wall having a lower edge and said wall having cups therein, flat elastic stays secured to side portions of said cups and biased to a slight outwardly bowed condition to preform the brassière into natural cups of shallow depth, an elastic tape secured to the entire lower edge of the fabric wall in stretched condition so as to be disposed beneath said cups and connected to the lower end portions of said stays to move such lower portions of the stays apart distances proportional to the amount of stretch given the tape, said tape also adapted to draw the brassière including the cups and stays against the breasts of the wearer with the cups expanding to receive the breasts and the stays moving over the sides of the breasts to further bow the same to thus alter the sizes of the cups in conformity with the size of the bust, an outer garment secured along its upper edge only to the upper portion of the fabric wall of said brassière whereby to accommodate itself naturally and freely to the conformation of said cups, side and rear portions for said outer garment, said tape having side and rear portions free of the side and rear portions of the outer garment to permit the tape to be passed about the body of the wearer in the application of the brassière before the outer garment is closed about the body, and fastening means on the rear portions of the outer garment for securing such outer garment about the body following the application of the elastic tape.
